COMBINED PLAYGROUND CLIMBER AND SLIDE

Harold W. Haubert, Mifflintown, Pa., assignor to The Mexico Forge, Inc., Reedsville, Pa., a corporation of Pennsylvania

Filed Oct. 2, 1964, Ser. No. 82,018

Term of patent 14 years

(Cl. D34—5)

Fig. 1.

Fig. 2.

FIG. 1 is a rear perspective view of a combined playground climber and slide, showing my new design; and FIG. 2 is a front perspective view thereof.

I claim:

The ornamental design for a combined playground climber and slide, substantially as shown.
